UNITED STATES PATENT OFFICE

FRED MATTHEWS, OF CHICAGO, AND EDWIN G. CHENOWETH, OF BLUE ISLAND, ILLINOIS,
ASSIGNORS TO CLINTON C. MURPHY, OF CHICAGO, ILLINOIS.

LADDER.

1,134,087.

Specification of Letters Patent. Patented Mar. 30, 1915.

Application filed October 7, 1914. Serial No. 565,487.

To all whom it may concern:

Be it known that we, FRED MATTHEWS and EDWIN G. CHENOWETH, citizens of the United States, and residents of Chicago and Blue Island, respectively, in the county of Cook and State of Illinois, have invented new and useful Improvements in Ladders, of which the following is a full, clear, and exact description.

10 Our invention relates to ladders that are particularly adapted for use on freight cars. The object of our invention is to provide a simply constructed strong and durable metal ladder the ends of the rungs of which are fastened in the side-rails thereof in such manner that the displacement thereof lengthwise or sidewise is prevented, and the turning of the rungs on their own axes, or the vibration thereof is entirely avoided. This 15 20 we accomplish by the means hereinafter fully described, and as particularly pointed out in the claims.

In the drawings: Figure 1 is a side elevation of one end of a box car showing my improved ladder applied thereto. Fig. 2 is a side elevation of said ladder removed from said car and drawn to a smaller scale. Fig. 3 is a vertical section taken on line 3—3, Fig. 1 of a lower broken away portion of the 25 ladder drawn to an enlarged scale. Fig. 4 is a transverse section taken on dotted line 4—4, Fig. 3, but with one side-rail of the ladder. Fig. 5 is a section of the side-rail similar to that shown in Fig. 4 showing in 30 dotted lines the position of the rung when first inserted and drawn to a larger scale. Fig. 6 is a section of a modified form of side rail similar to that shown in Fig. 5. Fig. 7 is a similar view of yet another modification. 35 40 Fig. 8 is a section of yet another modification to that shown in Fig. 7, but with a fragment of a rung thereof used in connection therewith. Fig. 9 is a perspective view of a fragment of the side-rail of our invention.

45 Referring to the drawings, A, A, represent the angle-iron parallel side-rails or frames of the ladder, and B, B, the metal rungs thereof. These rails are placed so that one of the flanges a of each rail will 50 project toward and be at right angles to the support to which the ladder is attached, and the other flange b of each rail will project toward the opposite rail parallel to said support. The flanges a of said rails are cut 55 away at the upper and lower ends thereof

at a suitable angle, and the end portions of the flanges b of the same are bent toward and then parallel to the said support to which they are secured by bolts or rivets or otherwise. The flange b or web portion of each rail is provided with correspondingly placed equi-distant openings or holes c, the diameters of which are such that the ends of the rungs can be inserted therethrough. These rungs B are, preferably, made of metal rods that are circular in section and the ends of these rods are provided with an offset portion d and extremities projecting a slight distance beyond said offsets whose axes are parallel to the axis of the part or hand-grasp of the rung disposed between the side rails, and in assembling the rungs and rails of the ladder, the former are placed at right angles to the rails and the extremities of said rungs are pushed inwardly through the holes c and then the rungs are moved until they are parallel to the support of the ladder so as to make the offset portion d of these rungs enter said holes and thus bring the outer curved surface of the extremities of the rungs into contact with the inner surface of the flanges b of the angle-iron rails, substantially as shown.

Between the rung-holes and the free edge of the flanges b of the rails in which said holes are made, the web is depressed inward to form a gutter or seat f in which the inner curved surface of the rung adjacent its offset portion is seated, and the web of the portion of said flange on the other side of the holes between the rung-holes and the angle of the angle-iron is bulged outward to form a reverse gutter or seat g in the inner surface of flange b to receive the outer curved surface of the extremities of the rungs.

In order to prevent any possible vibration of the ends of the rungs which may possibly happen owing to careless and defective workmanship, we prefer, when shaping the web of the flanges b of the angle-iron rails to form seats or gutters f, to incline the bottom of said seat or gutter f at an angle to the plane of the outer surface of said flange, substantially as shown. Thus, when one rail is secured to its support and the offset ends of the rungs are inserted through the holes c, said rungs are disposed substantially at right angles to the outer surface of flange b of the rail and then the other rail will be slipped over the outer ends of said rungs.

until the relative positions of said rails to the rungs is the same. The unattached rail on the outer ends of the rungs is pushed toward and against its support and secured thereto in such manner as to seat the ends of the rungs in gutters or seats *f*, holes *c* and inverted gutters *g*. In thus assembling the ladder, the rungs bear hard against the inclined surface of the bottom of the gutters *f*, which latter, while resisting the efforts to bring the rungs parallel to the support of the ladder, yield to a certain extent, and make the outer extremity of the rungs bear outward against their seats *g* and securely hold and clamp the ends of the rungs, and prevent any vibration thereof independent of the side-rails.

In Fig. 6 we show a modified form of our invention. This modification does not require any change in the construction of the rungs *B*, except the slight lengthening of the offset portions *D* thereof, and the only change in the construction of the rails is in the omission of the reverse seats *g*, shown in the first five figures of the drawings.

In Fig. 7 we show yet another modification of said ladder which differs from that shown in the preferred form to the extent of omitting the seats *f* and retaining the reverse seats *g* in the rails *G* thereof.

In Fig. 8 we show yet another modification in which the angle-iron rails are disposed so that the flanges *6* thereof that are parallel with the support of the ladder are placed next said support, and the other flanges *7* thereof project outward. These latter flanges *7* are provided with rung-holes *8* at about their centers of width, and between these holes and the free edge thereof its web is provided with a transverse gutter or seat on the side opposite that from which the horizontal flange projects, and between said rung-hole and the inner angle of the rail the web is provided with a reverse transverse gutter or seat *10*, shown only in dotted lines. The ends of the rung *2* are crooked somewhat, similar to that of a shepherd's staff, that is they are bent transversely for a distance corresponding to the distance between the free edge of flange *7* and the rung-hole; said ends are then given a return bend *3* of sufficient length to pass through said rung-hole and then have their extremities *4* bent transversely again parallel to the axis of the first mentioned transverse portion of the crook. The ends of the rungs *2* are inserted through holes *8*, as shown in the drawings, and when the rails of the ladder are fastened to its support the extremities *4* and the first mentioned transverse portions of the crooked ends of the rungs

will seat themselves in the transverse seat *9* in flange *7* of the side-rails and be securely held therein against displacement.

If desired, the bottom of seat *9* may be inclined toward the rung-hole *8*, and when the latter is set up may yieldingly resist the pressure of the rungs and securely hold the ends of the same against vibration.

What we claim as new is:

1. A ladder comprising metal side-rails having flattened portions provided with rung-holes therein and depressed transverse seats leading from said rung-holes, and metal rungs that have offset end portions that are adapted to extend through said holes and engage said seats.

2. A ladder comprising metal side-rails having a portion flattened parallel to the support thereof and provided with rung-holes therein, and depressed transverse seats leading from said rung-holes, and metal rungs that have offset end portions that are adapted to extend through said holes and engage said seats.

3. A ladder comprising angle-iron side-rails one of the flanges of each of which is parallel to the support thereof and provided with suitable rung-holes and depressed transverse seats therein between said holes and the free edge thereof, and metal rungs that have offset ends that pass through said holes and which engage said seats.

4. A ladder comprising angle-iron side-rails each having a portion that is parallel to the support of the ladder and provided with rung-holes and with depressed transverse seats leading from said holes the bottoms of which are inclined, and metal rungs that have offset portions that are adapted to extend through said holes and which engage said seats.

5. A ladder comprising angle-iron side-rails one of the flanges of each of which is parallel to the support of said ladder and has rung-holes in the same and opposite depressed transverse seats extending from said holes; one of said seats being made in the inner surface of said flange between the hole and the angle of the rail and the opposite seat being made in the outer surface between the hole and the free edge of the flange and having its bottom inclined.

In witness whereof we have hereunto set our hands this 29th day of September, 1914.

FRED MATHEWS.
EDWIN G. CHENOWETH.
